UNITED STATES PATENT OFFICE.

EDWARD J. RENISON, OF CHICAGO, ILLINOIS.

SEWING-MACHINE DRIVE.

Application filed May 25, 1923. Serial No. 641,285.

To all whom it may concern:

Be it known that I, EDWARD J. RENISON, a citizen of the United States, residing at Chicago, in the county of Cook and State of Illinois, have invented certain new and useful Improvements in Sewing-Machine Drives, of which the following is a specification.

This invention relates to improvements in sewing machine drives, and has for its principal object to provide a driving mechanism for sewing machines, which will permit the use of a common power actuated driving source for a battery of machines, and which will dispense with the belt ordinarily used for such devices, at the same time providing an efficient and satisfactory drive, together with means for controlling the actuation of the same. While this invention is especially adaptable for use with sewing machines in battery installations it is also available for use with satisfaction for the driving of single machine installations.

Another object resides in the means for control of the driving mechanism, whereby the operator may, by simple actuation of a foot treadle, throw into or out of operation the sewing machine.

Other objects reside in the details and arrangement of the structure, and with those objects outlined above, will be more fully disclosed and described in the following specifications and shown in the accompanying drawings, in which—

Figure 1 is a front elevation of an embodiment of my invention; and

Fig. 2 is a detail of the clutch mechanism utilized.

Like numerals refer to like elements throughout the drawings. 10 indicates generally a sewing machine of any desired construction, which is provided with the usual fly wheel 11, having the grooved driving pulley 12, which is provided with a groove 12^a of conventional construction, ordinarily used for the accommodation of a belt of cylindrical or other contour. The machine is supported upon the usual table 14, shown of the type ordinarily used where a battery or plurality of machines is arranged, which, in the embodiment shown consists of the rotating power shaft 15, carrying a beveled gear 16, which rotates therewith. Upright frame members 17 extend from the floor to support the table 14, provided with suitable journals for the shaft 15. Projecting in-

wardly from upright 17, is a bracket 17^a through which extends and in which is mounted the tube 18, in which in turn is the rotatable flexible shaft 19, secured at its end 60 to the beveled pinion 20, in constant mesh with bevel gear 16. Projecting upwardly from table 14 is the pedestal 25 having a laterally projecting bracket or lug 25^a in which is seated the tube 18. Journaled in a 65 suitable bearing in the upper portion of the pedestal 25 is the rotatable shaft 26, to which are secured the spaced collars 26^a on either side of the pedestal 25. Slidably mounted upon the shaft 26 is the collar 27 70 having a groove 27^a therein. In this groove 27^a are located the bifurcated extremities 29^a of bell crank 29, which is pivoted intermediate its extremities at 29^b to a bracket 30, extending downwardly from and secured 75 to the under side of the table 14. At its other extremity bell crank 29 is pivoted at 29^c to the actuating link or rod 31, in turn pivoted to foot actuatable treadle 32 or any suitable construction. 80

Attached to the outer extremity of shaft 26 is the cap 35 having projecting arms 36, each of the arms being slotted at its outer end to accommodate a pivoted finger 37. Each of these fingers is provided with the 85 engaging tip 37^a, of leather, rubber or other suitable material, see Fig. 2. Toggle links 38 are each pivoted at one end to lugs 27^b at the outer end of collar 27, and at the other end to the fingers 37. The arrangement is such that, as shown, shifting the collar 27 to the left as viewed in the drawings, will result in forcing finger tips 37^a into groove 12^a of pulley 12, firmly gripping the pulley so that thereafter rotation of the 95 shaft 26 will be imparted thereto. This clutching action is obtained by actuation of the foot treadle 32 in obvious manner, and declutching is accomplished by reverse movement, as will also be obvious. 100

With the structure of the character just described, a common source of power may be utilized to drive a plurality of machines and the operator of each machine is enabled to throw into or out of operation his or her 105 machine at will by a simple movement of the foot.

The grip of the clutch fingers may be increased by increased pressure on the foot treadle, which is an advantage incidental to 110 my construction. The above described construction dispenses with the use of the

leather belt and coacting pulley of present day use, which are prone to slip, are more expensive—due to necessary frequent replacement and repair—and which, unless 5 properly guarded, present a danger in that the goods being sewed or the clothing or hair of the operator may become entangled. Also with the belt and pulley drive a more complicated and expensive clutching mechanism or its equivalent is required.

It will be obvious that my invention is susceptible to alteration and modification and I do not wish to be restricted to the form shown and described except as recited 10 in the appended claims:

What I claim is—

1. In mechanism of the class described, in combination, a power actuated shaft, a flexible shaft rotatable thereby, a clutch member, a sewing machine having a rotatable drive wheel, means to transmit rotation of said flexible shaft to said clutch member, and means to engage said clutch member with said drive wheel.

2. In mechanism of the class described, in combination, a power actuated shaft, a flexible shaft rotatable thereby, a clutch member, a sewing machine having a rotatable drive wheel, means to transmit rotation of said flexible shaft to said clutch member, and means to engage said clutch member with said drive wheel, said last named means comprising a treadle and a shifting mechanism operably interposed between said clutch member and said treadle.

3. In mechanism of the class described, in combination, a power actuated shaft, a sewing machine having a rotatably grooved pulley, a flexible shaft rotated by said power

shaft, a clutch member rotatable by said flexible shaft, said clutch member being provided with pivoted fingers movable into and out of engagement with said grooved pulley.

4. In mechanism of the class described, in combination, a power actuated shaft, a sewing machine having a rotatably grooved pulley, a flexible shaft rotated by said power shaft, a clutch member rotatable by said flexible shaft, said clutch member being provided with pivoted fingers movable into and out of engagement with said grooved pulley, said fingers being provided with non-slip material at their contact portions.

5. In mechanism of the class described, in combination, a sewing machine having a rotatable pulley member, a rotatable clutch member movable into and out of engagement with said pulley, a flexible shaft operably attached to said clutch member, means to rotate said shaft, and means to shift said clutch member into and out of engagement with said pulley.

6. In mechanism of the class described, in combination, a sewing machine having a rotatable pulley member, a rotatable clutch member movable into and out of engagement with said pulley, a flexible shaft operably attached to said clutch member, means to rotate said shaft, means to shift said clutch member into and out of engagement with said pulley, said last named means comprising a bell crank engaging said clutch member, a foot actuatable treadle, and a link operably connecting said treadle and said bell crank.

In testimony whereof, I have subscribed my name.

EDWARD J. RENISON.
